Specification of Letters Patent.

Patented June 8, 1915.

Application filed March 16, 1915. Serial No. 14,827.

To all whom it may concern:

Be it known that I, WILLIAM ECCLES, a subject of the King of Great Britain and Ireland, and a resident of Chorlton-cum-Hardy, in the county of Lancaster, England, have made a new and useful Invention in Turbines, of which the following is a specification.

This invention relates to steam turbines of the kind in which a plurality of inlet nozzles are provided, some of which, hereinafter termed ordinary nozzles, can supply sufficient steam to enable the turbine to deal with ordinary loads while it is necessary that steam should be supplied through the remaining nozzles hereinafter termed overload nozzles when the load on the turbine is above the normal. It is a common practice with turbines of this type to provide two valves, one controlling the supply of steam to the ordinary nozzles and the other controlling the supply of steam to the overload nozzles, the total steam supply being controlled by a suitable throttle valve operated by the turbine governor in accordance with the load. In some instances both the nozzle control valves are arranged to be operated by the governor in accordance with the speed, but in other cases the overload valve is arranged to be opened and closed by hand. Where during long periods of time the load on the turbine is normal or less than normal or full load the steam consumption can be considerably improved by closing an additional or overload control valve, but if during such periods the load is liable to suddenly rise the attendant is afraid to close the valve in case a sudden overload should come on during his absence without giving time for the valve to be opened. This disadvantage is obviated where the overload control valve is operated by the governor in accordance with the speed, but the connection of the valve to the governor is often difficult and expensive to construct and in some cases the efficiency of the turbine at certain overloads may be seriously impaired.

According to the present invention automatic power operated means are provided

for suddenly and fully opening an additional steam supply valve such as the overload or full load valve if the load increases beyond the normal, said power operated means being either oil under pressure or live steam or a spring. This power means is brought suddenly and quickly into action by a trigger arrangement when the governor has moved to a predetermined extent by reason of the load rising above the normal amount. The closure of the additional or overload supply valve may either be effected by hand or means similar to those employed for opening the valve may be provided for suddenly closing the same when the load has fallen to a predetermined amount below the normal.

In order that the nature of the invention may be clearly understood, it will now be described with reference to the accompanying drawings in which—

Figure 1 is a view somewhat diagrammatic, showing the general arrangement of a turbine with an additional or overload supply valve operated in accordance with the present invention. Fig. 2 is a view drawn to an enlarged scale showing more clearly the connections between the turbine governor and the overload valve. Fig. 3 is a sectional view on the line III—III Fig. 2, showing the operated means for the overload valve.

Referring now to figures, a steam turbine is indicated at 1, the governor 2 of which is inclosed within a casing 3 and operates a sleeve 4 in the usual way in response to variations in the speed of the turbine. The sleeve 4 transmits its movement through a lever 5 pivoted at a fixed point 6 and a link 7 and lever 8 to a shaft 9. Keyed to the shaft 9 is an arm 10, and loosely mounted on said shaft is a two-armed triggered lever 11, having on one arm a projection 12, with which the arm 10 is adapted in certain positions to engage, and the other arm of which is provided with a notch 13, adapted to engage with a trip arm 14 keyed on a shaft 15. The shaft 15 has keyed thereon an arm 16, which is connected by a link 17 to one end of a lever 18 pivoted at a fixed point 100

19, the other end of said lever being adapted by means of a pin and slot connection or other suitable device to move a valve 20. An inlet valve which controls the admission of steam to additional or overload nozzles is shown at 21, Fig. 3, and is carried by a stem 22, the other end of which is provided with a piston 23, adapted to move in a cylinder 24. A spring 25 between the piston 23 and the outer end of the cylinder 24 is arranged to close the valve 21 and the other end of the cylinder is provided with a port 26 through which oil or other fluid under pressure can be admitted and released in accordance with the movement of the valve 20. The fluid under pressure is supplied through the pipe 27 and is exhausted through the pipe 28.

The operation of the device is as follows: So long as the load remains at or below normal the movement of the arm 10, occasioned by the movement of the governor sleeve 4, will never be sufficient to cause the arm 10 to engage with the projection 12 on the trigger lever 11, but when the load exceeds the normal and the amount of steam supplied through the normal load nozzles is insufficient to maintain the turbine at the proper speed the sleeve 4 will cause the arm 10 to move sufficiently far to engage the projection 12 and move the trigger lever 11 so as to disengage the arm 14 from the notch 13 whereupon said arm 13 will be moved under the influence of gravity or of a spring 29 and rotate the shaft 15. The rotation of said shaft, through the agency of the arm 16, link 17 and lever 18, will move the valve 20 in such a direction as to admit fluid under pressure from the pipe 27 through port 26 into the cylinder 24 thereupon quickly and fully opening the control valve 21. Steam will thus be supplied to the additional or overload nozzles to enable the turbine to take up the increase of load. Excessive movement of the arm 16 may be prevented by a suitable stop 30 if desired. Closure of the valve 21 when necessary may be brought about by forcing the arm 16 away from the stop 30 thereby moving the valve 20 so as to open the cylinder 24 to the exhaust pipe 28 whereupon the spring 25 acting on the piston 23 will close the additional or overload valve and cut off the steam to the overload nozzles. The arm 14 will also be reengaged with the notch 13 of the trigger lever 11 and be held in position to be operated when the load again increases above the normal.

The invention is obviously also applicable to apparatus in which the supply of steam to the overload nozzles is controlled by some form of nozzle cutout instead of by a valve such as illustrated.

It will be observed that in the arrangement shown in Fig. 2, the valve 21 which controls the supply of fluid under pressure to the cylinder 24 is located in close proximity to said cylinder and in such a case instead of operating the piston 23 by fluid under pressure the lever 18 may be arranged to operate a retaining catch for the piston 23 adapted to be actuated by a spring to open the valve 21 without the intervention of any fluid under pressure. The fluid operated device has, however, the advantage that if the additional or overload valve or nozzle cutout is arranged as a part of the turbine which is not easily accessible only a simple pipe connection from the cylinder 24 to the chamber containing the valve 20 governing the supply of fluid to said chamber is required, thus rendering the device easy of application.

It will be understood that the expression "overload" hereinabove employed does not necessarily mean loads above full load, as in some cases the normal load is less than full load. For this reason the words "additional" supply valve are employed as an alternative to "overload" valve.

Having now particularly described and ascertained the nature of my said invention and in what manner the same is to be performed, I declare that what I claim is:

1. In combination with a quick opening overload valve for turbines, a motor for actuating said valve, and governor controlled mechanism for controlling the operation of said motor, comprising a governor actuated member, a trip mechanism controlled by said member, and means released by said trip mechanism for controlling said motor to open said valve.

2. In combination with a quick opening turbine valve, a motor for actuating said valve, and a governor controlled mechanism for controlling the operation of said motor, comprising a governor actuated member, a trigger member actuated by said governor actuated member when the governor actuated member is moved to a determined position, and a member held in an inoperative position by said trigger member, and disengaged therefrom when said trigger member is actuated by said governor actuated member, and means actuated by said last mentioned member for causing said motor to open said valve.

3. In combination with a quick opening turbine valve, a pressure actuated motor for opening said valve, and governor controlled mechanism for controlling the operation of said motor, comprising a governor actuated member, a trigger lever adapted to be engaged and actuated by said member when said member is moved to a determined posi-

tion, a trip arm normally held in an inoperative position by said lever and adapted to be disengaged from said lever when said lever is actuated by said member, a valve for delivering actuating fluid to said motor, and means actuated by said trip lever for actuating said valve.

⁵ Copies of this patent may be obtained for five cents each, by addressing the "Commissioner of Patents, Washington, D. C."

In testimony whereof, I have signed my name to this specification in the presence of two subscribing witnesses.

WILLIAM ECCLES.
